ATTORNEY

UNITED STATES PATENT OFFICE.

LEO E. EVSLIN, OF NEW YORK, N. Y.

CAPSULE FOR ANTISEPTICS AND THE LIKE.

1,350,304.

Specification of Letters Patent. Patented Aug. 24, 1920.

Application filed June 19, 1918. Serial No. 240,808.

To all whom it may concern:

Be it known that I, LEO E. EVSLIN, residing at New York, in the county and State of New York, have invented certain new 5 and useful Improvements in Capsules for Antiseptics and the like, of which the following is a specification.

This invention relates to a capsule for antiseptics and the like, and the object of 10 the invention is to provide a container or capsule such as may be formed of suitable sheet metal and which will permit the fumes of the antiseptic material contained therein to flow freely therefrom.

15 A further object is to provide a capsule which may be readily opened and closed for facilitating recharging, etc.

Other objects and aims of the invention, more or less specific than those referred to 20 above, will be in part obvious and in part pointed out in the course of the following description of the elements, combinations, arrangements of parts and applications of principles, constituting the invention; and 25 the scope of protection contemplated will be indicated in the appended claim.

In the accompanying drawings which are to be taken as a part of this specification, and in which I have shown merely a preferred form of embodiment of the invention:

Figure 1 is a horizontal sectional view through a capsule constructed in accordance with this invention, and illustrating a 30 quantity of disinfecting material therein, and

Fig. 2 is a top plan view of the capsule shown in Fig. 1, a portion of the structure being illustrated in horizontal section substantially upon the plane of line II of Fig. 1.

Referring to the drawings for describing in detail the structure which is illustrated therein, the reference character L indicates the base or body portion of the 45 capsule, while the reference character G indicates the top or cover part.

The body portion L is formed with a plurality of projections 1 protruding laterally from the side walls 2 thereon 50 at substantially equi-distant points around its periphery. These projections may be formed in any desired manner, but are preferably formed by being pressed into the material of the body. They each 55 provide an inclined upper wall surface

3 serving as guides for guiding the cover G into position.

The cover G is formed with an annular flange portion 4 thereon adapted to telescope downwardly over the walls 2 of the 60 body. The lower edge portion 5 of this flange is preferably of a diameter which is slightly less than the diameter of the circle defined by the outer extremities of the projections 1 on the body, so that in applying 65 the cover, the lower edge 5 engages the surfaces 3. Slight pressure upon the cover will cause the edge 5 to spring, or straighten out, between the projections 1 sufficiently to allow the lower edge portion of the flange 70 4 to pass below the point of greatest protuberance of the projections 1.

Above the lower edge 5 the flange 4 is bulged outwardly to some extent for accommodating the projections 1, the bulge being 75 only sufficient substantially to permit the flange 4 to reassume its original circular form. Sufficient pressure is still maintained against the projections 1 to hold the cover against undesirable movement relatively to 80 the body.

The region of greatest bulge in the flange 4 is in a plane such that when the projections 1 rest therein, the top wall 6 of the cover is spaced somewhat above the upper 85 edge 7 of the body, substantially as indicated in the drawings, thus leaving a free passageway, as 8, between the upper edge of the body and the inner surface of the wall 6. The flange 4 is also of such size as to 90 leave an open space, as 9, between the inner surface thereof and the outer surface of the wall 2 of the body at the localities between the projections 1. The fumes from the disinfecting material, as H, within the 95 body may thus pass freely through the passageway 8-9 and outwardly from the capsule at all times.

If desired, a plurality of apertures, as 10, may be provided in the flange 4 for facilitating a better circulation of air. The openings 10 may be duplicated at any other points as desired, but usually they are not required.

A container, or capsule, constructed as above described, may be made of any size 105 from a quarter of an inch or less in diameter, to the size illustrated in the drawings, or even larger, with equal effectiveness in all instances. The cover may be readily attached or removed at will. The passageway, 110

or passageways, for the egress of fumes is at all times free and clear. As above suggested, the apertures, as 10, may be omitted, and in this instance the passageways for the egress of fumes are opened and exposed for cleaning by the simple operation of removing the cover. In fact the act of removing the cover itself is, in most instances, sufficient for cleaning all of the passage-
ways.

In addition, the passageways are of such a character as are not likely to be clogged, at any time, by the disinfecting material.

As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

- 25 1. A capsule of the class described having a passageway therein providing for the egress of fumes therefrom, means whereby the capsule may be opened, and said means being of a character such that the opening 30 of the capsule separates the parts forming said passageway for the purpose set forth.
2. A capsule comprising a body part and a cover part, and means interengaging between the body part and the cover part providing a passageway for the passage of air through the capsule.
3. A capsule comprising a body part and

a cover part, means interengaging between the body part and the cover part providing a passageway for the passage of air through the capsule, and said means being of a character such that removal of the cover part separates the parts forming said passageway for the purpose set forth.

4. A capsule comprising a body part and a cover part, one of said parts having a flange thereon telescoping the second part, and the second part having a plurality of projections formed thereon for engaging the flange of the first part to retain said flange 50 spaced from the second part intermediate said projections to thereby provide a plurality of passageways for the passage of air through the capsule.

5. A capsule comprising a body part and a cover part, the cover part having a flange thereon telescoping the body part, the body part having a plurality of projections formed thereon for engaging the flange of the cover part to retain said flange spaced 60 from the body part intermediate said projections to thereby provide a plurality of passageways for the passage of air through the capsule, and said flange being shaped to engage said projections in a manner to retain the cover out of engagement with the upper edge of the body.

In testimony whereof I affix my signature in the presence of two witnesses.

LEO E. EVSLIN.
